(57) **CLAIM**

We claim the ornamental design for a modular tool container, as shown and described.

DESCRIPTION

FIG. 1 is an exploded, perspective view of a modular tool container showing the new design.

FIG. 2 is a perspective view of a portion of the modular tool container of FIG. 1, shown separately to show aspects of the design that are not visible when combined; and,

FIG. 3 is a top view of a portion of the modular tool container of FIG. 1, shown separately to show aspects of the design that are not visible when combined.

Portions of the modular tool container shown in dash-dot lines form no part of the claimed design. Portions of the modular tool container shown in dot-dot lines indicate boundaries of the claimed portions and form no part of the claimed design.
